WILLARD A. PETTEYS, OF WILCOX, NEBRASKA.

DUST AND CHAFF COLLECTOR FOR GRAIN-ELEVATOR HEADS.

Application filed July 22, 1924. Serial No. 727,593.

This invention relates to improvements in dust and chaff collectors, and more particularly to dust and chaff collectors for grain elevator heads, and the objects of the invention are to provide a simple and economically constructed device that can be fitted to a grain elevator head whereby the chaff, dust and the like, is efficiently and quickly separated from the grain.

Further objects are the provision of a dust and chaff cleaner for elevator heads in which the several parts are so arranged as to give more satisfactory and durable service and which is not liable in continuous operation to get out of order.

With the foregoing and other objects in view, the invention consists essentially in the novel construction and arrangement of parts as described in the present specification with the example of my invention illustrated by the accompanying drawings forming part of the specification and claimed in the accompanying claims.

Referring now to the drawings, in which like characters of reference indicate corresponding parts in each figure:

Figure 1 is a front elevation of the device as a whole.

Figure 2 is a top plan view.

Figure 3 is a side elevation from the right hand side of the machine.

Figure 4 is a section on line 4—4 of Figure 2.

Figure 5 is a section on line 5—5 of Figure 1.

Figure 6 is a section on line 6—6 of Figure 1.

Figure 7 is a section on line 7—7 of Figure 3.

Figure 8 is a section on line 8—8 of Figure 1.

Figure 9 is a sectional detail on line 9—9 of Figure 2.

Figure 10 is a perspective detail of an air-controlled door.

Figure 11 is a perspective detail of the baffle plate.

In the drawings, A designates an elevator head as a whole comprising a casing 10 transversely of which extends a shaft 11 provided with suitable bearings 12 and 13 on the supporting ribs 14 and 15 extending longitudinally on the outside of the casing. Fixedly mounted on this shaft within the casing is the elevator roller 16 on which is the elevator belt 17 provided with a plu-

rality of pockets 18. On the protruding ends of the shaft are keyed the sprocket drive wheel 19 chain connected to the source of power, and the drive pulley 20, 60 respectively. The pulley 20 is connected by a belt 21 to a smaller pulley 22 carried by a cross counter-shaft 23 suitably supported in bearings on a detachable stand 24 adapted to engage and disengage through the 65 recessed arms 25 and 26 with the casing 10. On the other end of the shaft 23 is mounted the driving pulley 27 connected by a belt 28 to a pulley 29 hereinafter more fully described, the foregoing construction being 70 more particularly illustrated in Figures 2, 3, 4 and 5.

The inside of the casing or head 10 is provided with restricted and slanting partitions 30 and 31 adjacent each side of the 75 elevator roller 16, as shown in Figure 5, and is provided at the top with a detachable lid or cover 32. Adjacent one side and extending partially and vertically upwards is a partitioning member 33 forming a compartment 34 with an opening in the bottom thereof 35, and into this compartment the grain carried by the elevator pockets 18, as illustrated in Figure 5, is, in operation, 80 adapted to be discharged. Within this 85 compartment 34 and suitably arranged is a detachable baffle plate or spreader 36 consisting of a pair of parallel spaced supporting members 37 and 38 (see Figure 11), bridged by a restricted cross member 39 so 90 that when placed in position as shown in Figure 5 the grain discharged in the elevator will contact first with the bridge member 39 and then drop on each side thereof through the openings 40 and 41 95 formed between the bridge member 39 and the side of the elevator and partition in the elevator, 33, respectively.

It will thus be seen that the grain discharged from the elevator will in its travel 100 downwardly be intercepted and spread and while so spread subject to the action of the blower, thus facilitating to a very great extent the cleaning of it by the more rapid and efficient elimination or separation of 105 dust and other foreign material therefrom.

Referring now more particularly to the means for cleaning the grain, as illustrated in Figures 2, 3, 8 and 9, this consists of a suitable stand 42 adapted to detachably engage with an opening in the base of the casing. On this stand is detachably mounted

a box casing member 44 to which is attached a housing 45 for a fan. This casing extends parallel with the side of the elevator head and is provided at the end opposite the fan housing with an extension 46 divided into two compartments 47 and 48 by a partition 49, the two compartments, it will be noted, opening into the single compartment 50 of the box casing which in turn communicates with the fan housing 45 in which is operatively mounted a fan 51 on a shaft 52 extending through the fan housing and through the casing and suitably journaled therein. This shaft 52 extends beyond the fan housing 45 to carry the pulley 29 belt-connected to the pulley 27, and whereby the fan, on the driving mechanism being operated, is also operated. Above the extension 46 is adapted to fit a head or cover in the form of a casing 53 having a partition therein 54 registering with the partition 49, forming the two compartments 55 and 56 corresponding to the compartments 47 and 48. The compartments 55 and 56 are connected through chutes 57 and 58 with openings 59 and 60 in the side of the elevator head whereby, on the fan being operated concurrently with the operation of the elevator and the discharge of the grain, as illustrated in Figure 5, into the compartment 34, a suction draft is provided for the grain while it is actually in the air and thus extracting from it all dust and dirt, throwing the same through the chutes 57 and 58 into the compartments 55 and 56 and thence into the compartments 47 and 48 and from there into the grain box casing compartment to be finally discharged through the opening 61 (see Figures 7 and 8). To regulate the strength of this draft I provide a spring-held door 62, as illustrated in Figure 10, and adapted to partially open or partially close the entrance of the compartment 49 to the main box compartment 50 to thus break the force or rush of the draught.

63 is a sliding door in the end of the elevator head.

From the foregoing it is believed that the operation and satisfactory results obtained from my improved dust and chaff eliminator or collector will be apparent. As already mentioned, when the fan or other drive from the source of power operates the sprocket wheel 19 through the shaft 11, the pulley 20 and the roller 17, the elevator mechanism will be operated, and simultaneously with it through the belt and pulley mechanism the fan 51, thereby creating the necessary draft for automatically cleaning the grain in transit, the clean grain being discharged through the opening 35, and the dust, dirt and chaff being discharged through the opening 61.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:

1. A dust and chaff collector for grain elevator heads comprising in combination with an elevator head, a casing adapted to detachably engage with the elevator head, a fan in the casing, a main compartment in the casing and compartments communicating with said main compartment, a detachable head for the casing and compartments formed in said head registering with the compartments in the casing, air chutes connecting the casing head with the elevator head whereby, on the fan being operated a suction air blast is created from the elevator head through said casing.

2. A device as claimed in claim 1 in which a baffle plate is provided in the elevator head to temporarily check the grain in transit to subject it to the suction air blast.

In witness whereof I have hereunto set my hand.

WILLARD A. PETTEYS.
